UNITED STATES PATENT OFFICE.

SAMUEL SMITH, OF CHICAGO, ILLINOIS.

ROTARY STEAM-ENGINE.

SPECIFICATION forming part of Letters Patent No. 453,247, dated June 2, 1891.

Application filed March 18, 1891. Serial No. 384,881. (No model.)

To all whom it may concern:

Be it known that I, SAMUEL SMITH, a citizen of the United States, residing at Chicago, in the county of Cook and State of Illinois, 5 have invented certain new and useful Improvements in Rotary Steam-Engines; and I do hereby declare that the following is a full, clear, and exact description of the same, reference being had to the annexed drawings, 10 making a part of this specification, and to the letters of reference marked thereon.

This invention relates to certain new and useful improvements in rotary steam-engines; and it has for its objects, among others, to provide an improved device of this character 15 wherein the cylinder fitted with piston-hub forms three immovable sides of the steam-space, the piston forming the fourth side, receiving the effects of the introduction and expansion of the steam. I so arrange the cylinder and piston plate and hub that the cylinder acts as a guide, imparting to the piston a reciprocating motion by the revolution of the hub. I provide steam-ports in the piston-hub, 20 in such relation to an opening in the packing-plate that the steam-supply is reduced to a controlled part or fraction of a revolution of the piston. I provide for the controlling of the steam-supply by the force of the exhaust- 25 steam ejected through the exhaust-chamber.

Other objects and advantages of the invention will hereinafter appear, and the novel features thereof will be specifically defined in the appended claims.

30 The invention is clearly illustrated in the accompanying drawings, which, with the letters of reference marked thereon, form a part of this specification, and in which—

Figure 1 is a front elevation of my improved 35 rotary engine with the steam-pipe broken away and the shaft in section. Fig. 2 is a vertical section through the same, taken at right angles to the steam-pipe. Fig. 3 is a view looking at the reverse side of Fig. 1 40 with the end plate removed. Fig. 4 is a vertical section through Fig. 1 at right angles to Fig. 2. Fig. 5 is a section on the line $x-x$ of Fig. 4. Fig. 6 is a horizontal section on the line $y-y$ of Fig. 4. Fig. 7 is a perspective view 45 of the piston hub and plate removed. Fig. 8 is a sectional detail, which will be more particularly hereinafter referred to.

Like letters of reference indicate like parts throughout the several views in which they occur.

Referring now to the details of the drawings by letter, A designates flanged base-pieces, to which are bolted the disks or end plates A', which are made in one or two parts and to which are secured the central 55 end disks A², which are provided with bearings a for the shaft and are preferably detachable for the purpose of affording ready access for the purpose of repairs or examination.

The cylinder B is composed of the sides B' and the plate B², secured to the sides and forming the outer side or periphery. It is provided with an exhaust-opening b and a packing-box b' , as seen in Fig. 4.

The shaft C is made in two parts, with flanges c , bolted to and forming the outside of the piston-hub C', as seen clearly in Fig. 2. One of the flanges has openings or steam-ports C², as seen in Figs. 2 and 4, also a groove 60 c^2 to receive a steam-tight plate E, as seen in Fig. 2, and also a seat for the packing-ring c^4 , which is fitted steam-tight thereto and held against the disk A² by springs c^5 , as seen in Fig. 2. The opposite flange is shaped to receive a packing-ring c^6 , which is held against the piston-hub in the same manner, this packing-ring being beveled, as shown, the shape 65 causing equal wear on the face and sides.

The piston-hub C' is formed in two like 70 parts, as seen in Fig. 4, each provided with a steam-port C³ and with a space between for the piston-plate D, which consists of a plate with packing-strips d on the ends and sides. It may also be provided with interchangeable 75 strips, if desired. This plate is movable in the hub, as will hereinafter appear. At one end of the hub is a circular-shaped plate E, with an opening E' and a groove e for the flange of the valve F, and is held steam-tight 80 on the side of the piston-hub by rods and springs e' or any other suitable means.

Steam and exhaust chambers are formed by the walls G, bolted to the parts A and B². In the exhaust-chamber is fixed a plate G', 85 with spring G², fixed on the shaft G³, one end of which is extended into the steam-chamber and is made steam-tight by the stuffing-box G⁴. In the steam-chamber it is provided with 90

and carries an arm G^5 , connected to the valve F by the rod g. The said valve is a curved plate with side flanges, as shown best in Fig. 7, and an abutment g' on its lower side, and 5 on top it is provided with a lug g² for the said rod. The other end of the shaft G³ is extended through the outside disk, where it is provided with an index-hand g⁴, showing on a scale g⁵ the exact position of the valve and 10 the amount of steam-supply.

H is a curved bar located in a recess in the plate B² and by means of springs held steam-tight against the piston-hub. Its shape prevents the piston-plate from resting on it alone 15 in passing. The recess h brings the steam-pressure on the side of the bar, so it will not be forced down.

I is a drip for the condensed water, and it terminates in a valve i.

20 J and J' are drips for the steam and exhaust chambers.

K is a thin plate fastened to the ends and surrounding the cylinder, steam, and exhaust chambers.

25 The steam-space in the cylinder is determined by the difference between the diameter of the piston-hub and the length of the piston-plate, which also governs the shape of the cylinder. The plate B² is on any point 30 an equal distance from the opposite side through center of the piston-hub, the distance being the length of the piston-plate.

35 Various modifications in detail may be resorted to without departing from the spirit of the invention or sacrificing any of its advantages.

The operation is as follows: Steam is admitted through the steam-pipe L in the ordinary way and escapes into the steam-chamber surrounded by the disk A², part of the 40 flange of the piston-hub, and the packing-plate and packing-ring. Supposing the piston-hub to stand in the position in which it is shown in Fig. 4, steam will pass through 45 the opening E' in the plate E and escape through the steam-port in the piston-hub terminating in the opening C³, as seen in Fig. 7, and into the cylinder behind the piston-plate, which it will cause to revolve. The 50 steam will continue to rush in till the piston-plate is in the position shown at W in Fig. 3, and now the port is past the opening E' and the supply is cut off. The expansion of the steam admitted will continue to revolve 55 the piston till it reaches the position in which it is shown at Z in Fig. 3, when the hub and the other end of the plate are in the first position, and steam is admitted through the port and the cut-off and expansion repeated. The 60 expanded steam is driven in front of the piston-plate through the exhaust-opening b into the exhaust-chamber, where it strikes the plate G', raised by its spring G². Supposing the exhaust-steam has sufficient force to drive 65 the plate down to a vertical position, it will thus, by the aid of the shaft G³, arm G⁵, and

rod g, move the valve F so as to close the opening E', or nearly so, thus reducing the steam-opening to a small fraction of its normal size and admitting a corresponding 70 amount of steam only, at the same time cutting off the steam at V in Fig. 3. When the speed diminishes, either by adding to the load or by change of steam-pressure, the plate will immediately be raised and the valve 75 opened. It is apparent that this arrangement and construction of parts will control the speed of the engine with changeable load, making it perfectly automatic in consumption of steam. 8c

At O, I have shown a pipe and at P a valve in said pipe, which pipe connects the steam-space and the cylinder, to be used when the engine is at rest, and the piston-plate being in a position between W and Z, the valve being then opened and steam enough admitted to turn the engine over. The pressure on the piston-plate is continuous, as the moment the steam has lost its force on one end it is exerted against the other, making it independent of momentum for any part of the revolution. Steam is introduced absolutely at the same position of piston-plate, no matter what the speed of pressure, and into the smallest possible space, consequently retaining its most 90 compressed state, and as the volume increases the piston-plate gradually presents more of its face for reception of the pressure. The steam-space may be made larger or smaller to conform with the desired speed by making 95 the piston-hub larger or smaller in proportion to the cylinder. 100

The engine has few moving parts and consequent small amount of friction. The wearing parts are interchangeable. 105

What I claim as new is—

1. In a rotary engine, the combination, with the cylinder having exhaust-opening, of the hinged plate for closing said opening, the shaft to which the plate is attached, and an index and scale for indicating the position of the valve, as set forth. 110

2. In a rotary engine, the combination, with the piston-hub, the cylinder having exhaust-opening, and the valve on the piston-hub, of the hinged plate closing the exhaust-opening, its shaft, and pivotal connections between the shaft and valve, substantially as specified. 115

3. In a rotary engine, the combination, with the cylinder having exhaust-opening, the rotary piston-head, and its plate, of the curved valve on the piston-hub closing a port therein, the hinged plate for closing the exhaust-opening, the shaft on which it is hinged, and the arm and rod pivotally connecting the shaft 120 and valve, substantially as specified.

4. In a rotary engine, the combination, with the piston-hub having steam-port and guide-groove, of the curved valve having a lug fitting the groove, the hinged plate for closing 125 the exhaust-opening in the cylinder, the pivotal connections between the shaft on which

the said plate is hinged and the valve, and the spring acting on the plate to normally keep it to its seat, substantially as specified.

5. In a rotary engine, the combination, with the exhaust-chamber, of the valve sliding on and closing a port in the piston-hub, and the hinged plate closing the exhaust-opening from the cylinder, whereby the steam-supply is controlled by the force of the exhaust-steam ejected through the exhaust-chamber, substantially as specified.

6. In a rotary engine, the combination, with the cylinder and the piston-hub and its plate, of the valve sliding on the piston-hub to close 15 a port therein, the spring-actuated hinged plate for the exhaust-opening in the cylinder, the pivotal connections between the plate and

valve, the drip I, and the curved bar H, with adjacent recess, substantially as and for the purpose specified.

7. In a rotary engine, a piston-hub formed of two like parts each with a steam-port, with a space between the adjacent edges of the two parts for the reception of the piston-plate, and a curved sliding valve guided circumferentially on one face of the said hub, substantially as specified.

In testimony that I claim the above I have hereunto subscribed my name in the presence of two witnesses.

SAMUEL SMITH.
